9 Claims. (Cl. 101—378)

The present invention relates to printing and more particularly to the attachment of lead printing plates to printing rollers and particularly to the operation of the movable lead plate retaining pawls and the mechanism for operating the pawls.

Heretofore various means have been used for securing the lead printing plates to the rotary printing rollers, but none have been entirely satisfactory because of the inequality of the forces applied by the retaining pawls and the mechanism for adjusting the pawls has been difficult to manipulate so that failure occurred with resultant loss in time and production and frequently in damage to the plate.

An object of the present invention is to provide a printing roller with means to retain the printing plates in fixed position during the printing operation and which provides for readily removing and replacing the plates as required.

Another object of the invention is to provide indicating means to show the condition of the lead plate retaining pawls so that the attendant can determine the condition of the attachment of the lead plate without delay.

Another object of the invention is to provide means to remove the lead plates from the same operating shaft which operates the pawls for retaining the printing plates.

Other and further objects will be apparent as the description proceeds and upon reference to the accompanying drawings wherein:

FIGURE 1 is a longitudinal view of a major portion of a printing roll with some parts in section and showing the movable and fixed pawls for retaining the lead plates and also showing the means for moving the lead plates away from the roller.

FIGURE 2 is an enlarged axial section taken on line 2—2 of FIGURE 1 through the pawl operating shaft and showing the accentrics, bearings and helical gear on the shaft and showing a portion of the segmental gear in mesh with the helical gear.

FIGURE 3 is a radial section taken on line 3—3 of FIGURE 2 showing the meshing of the segmental gears with the cooperating helical gears for operating the pawl operating lined shaft.

FIGURE 4 is a radial section taken on line 4—4 of FIGURE 1 showing the lock keys for retaining the segmental gears in position and also showing the removable levers for operating the segmental gears.

FIGURES 5 and 5A are enlarged vertical sections taken along line 5—5 of FIGURES 1 and 2, showing the movable pawls in projected and retracted positions, respectively.

FIGURE 6 is a fragmentary cross-section taken on broken line 6—6 through the pawl operating shaft and the L-shaped levers providing the pawl structure.

FIGURE 7 is a fragmentary section taken on line 7—7, showing the stop and the spring pressed cartridge arrangement for taking the reaction of the other arm of the L-shaped pawl lever.

FIGURE 8 is an enlarged vertical radial section taken along the line 8—8 of FIGURES 1 and 2, showing one of the lead plate-releasing arms in operative plate-releasing position.

2

FIGURE 9 is a fragmentary axial section taken on line 9—9 of FIGURE 4 with the assumption that the showing is rotated 180° to place with the operating lever in a vertical upright position.

FIGURE 10 is an enlarged vertical section, taken on line 10—10 of FIGURES 1 and 2, showing the bearing arrangement for the pawl operated shaft and the fastening bolts for securing the parts in assembled relation.

FIGURE 11 is an enlarged vertical section, similar to FIGURE 5, showing a modified leaf-spring construction for the other arm of the L-shaped pawl lever.

Briefly, the present invention provides a pair of pawl operating shafts in diametrically opposed channels in a printing roller with accentrics on the shafts providing bearings for L-shaped pawl levers of which one arm forms the movable pawl for retaining the lead plate and the other arm reacts against a stop or a spring to provide an even pressure to retain the lead plate and segmental gear means are mounted on the roller and movable in limited arcuate paths to cooperate with helical gears on the pawl operating shafts to operate the pawl in a desired manner. Suitable latching means are provided to retain the pawl operating shafts in operative or inoperative positions with the movement being controlled by removable levers which levers can only be removed in the limit positions. The same pawl operating shafts also provide for positively releasing the lead plates.

A printing roller 12 carries a plurality of lead printing plates 13, 14 and 15 with the axial length of the lead plates being approximately one-quarter of the length of the plate cylinder and the width of the lead plate approximately half the circumference of the roller. The roller is provided with a pair of diametrically opposed axially extending channels 16 and 17 and in each channel a pawl operating shaft 18 is mounted for rotary movement and such shaft each carries spline grooves 19 at one end with screw threads 19, 19' adjacent each end of the splines. The shaft 18 carries a plurality of accentrics 20, 21, 22 . . . and pivotally mounted on each eccentric is an L-shaped lever with the apex of the L-shaped lever serving as the strap 76 around the eccentric and such L-shaped lever provides the movable pawls 23 to 30, inclusive.

Bearings are formed by the members 31 to 35, inclusive, as shown in FIGURE 10 where the member 32 is secured in position in the channel by bolts 32A, 32B and such bearing part cooperates with bearing member 32C which is held in proper adjusted position by the shim or spacer 38, thereby providing for accurate location of the shaft 18 with suitable bearing metal 41 surrounding the journal of the shaft in a well-known manner.

A flanged bushing 43 is threaded onto screw threads 19' and abuts against a side surface of a helical gear 44 splined onto the splines 19, while a washer 45 engages the other surface of the helical gear 44 and is held in position by the lock nut 46 threaded onto the screw threads 19'', with the pitch of the thread 19'' being different from that of the thread 19'. The flanged bushing 43 is provided with a radial aperture 47 for receiving a tool such as a spanner wrench or the like and an aperture 48 is provided in the segmental gear 59 to provide access to the lock nut 46 so that the proper position of the helical gear 44 can be obtained.

As seen in FIGURES 1, 7, 10 and 11, fixed pawls 49 to 56 are provided on the surface of the roller 12, being secured thereto by screws 49A, as shown in FIGURE 10, and such fixed pawls are mounted on a suitable bar which is received in a portion of the channels 16 or 17, with the fixed pawls in one groove extending in the opposite direction from the movable pawls, as shown in FIGURES 5 and 6, so that the movable pawl engages one lead printing plate while the fixed pawl engages the other printing plate.

and the attendant therefore knows the roller is in non-printing or inoperative condition.

It will be apparent that changes may be made in the actual construction within the spirit of the invention as defined by the valid scope of the appended claims.

What is claimed is:

1. A printing roller with mounting means for lead plates comprising a roller having stepped shaft portions and having diametrically opposed axially extending channels in the periphery thereof, a pawl operating shaft having eccentrics spaced therealong rotatably mounted in each channel, an L-shaped lever pivotally mounted about its apex on each eccentric, one arm of each L-shaped lever serving as a pawl for connection to one end of one lead plate and adapted to be projected beyond and retracted within the periphery of the roller, said pawl operating shaft being splined on one end, a helical gear splined on said splined end of said shaft, screw threads of different pitch adjacent each end of the splined portion of said shaft, a flanged bushing threaded on one of said screw threads, and a lock nut on the other of said screw threads with means to adjust the flanged bushing and lock nut to vary the axial position of the helical gear, fixed pawls mounted on said roller adjacent the movable pawls and extending in the opposite direction to secure the other end of another lead plate, a pair of internally toothed segmental gears mounted on the stepped shaft portion of said roller each cooperating with one helical gear whereby arcuate movement of each segmental gear causes rotation of its associated helical gear and thereby operation of the pawls mounted on the cooperating pawl operating shaft, each segmental gear being provided with an outwardly opening rabbet at each axial end, a retaining collar having a rib fitting into each rabbet and fixed to said roller retaining said segmental gears in operative relation, means to limit the movement of each segmental gear between pawl projected and pawl retracted positions, an operating lever receivable in a radial aperture in each segmental gear, a lock key mounted in one shaft step of said roller and movable into a recess in the cooperating bearing portion of its associated segmental gear, resilient means urging said lock key into said recess to prevent relative angular motion between said roller and said segmental gear, an indicating pin mounted in said segmental gear and pressed toward said lock key to indicate the pawl projected position, a retaining pin mounted in said gear segment for axial movement and of a length to extend into the radial lever receiving aperture, and into a registerable recess in one retaining collar, and adapted to be received in a recess in the portion of the operating lever received in the gear segment, said one retaining collar having a second pin receiving recess with which said pin may register in another position of said pawls, the other arm of each L-shaped lever extending toward the adjacent fixed pawls of the other lead plate, a follower on said other arm of each L-shaped lever, a stop limiting the movement of each follower on the other arms away from said stationary stop, a coil spring cartridge assembly reacting between said stationary stop and the other surface of said other arm of each pawl whereby rotation of said pawl operating shaft will cause said L-shaped levers to move the pawl arms into projected or retracted position, a plurality of plate releasing arms pivotally mounted on said pawl operating shaft, a key between each releasing arm and said pawl operating shaft providing lost motion in causing operation of said releasing arms, take up spring means reacting between said releasing arms and said roller preventing vibration of said releasing arms in inoperative position thereof.

2. Equipment for retaining and removing one end of a lead plate for a printing roller comprising a support having a channel therein, a pawl operating shaft having eccentrics spaced therealong rotatably mounted in said channel, an L-shaped lever pivotally mounted about its

apex on each eccentric, one arm of each L-shaped lever serving as a pawl for connection to one end of a lead plate and adapted to be projected beyond and retracted within the support, the other arm of each L-shaped lever extending in a direction generally parallel to the surface of the support, a stop limiting the movement of said other arm away from said surface of the support, biasing means reacting between said support and said other arm to urge said other arm toward said stop whereby rotation of said pawl operating shaft will cause said L-shaped lever to move the pawl arm into projected or retracted position, a plurality of plate releasing arms pivotally mounted on said pawl operating shaft, a key between each releasing arm and said pawl operating shaft providing lost motion for causing operation of said releasing arms, take up spring means reacting between said releasing arms and said support preventing vibration of said releasing arms, and means to operate and retain said pawl operating shaft for projection and retraction of said pawls and releasing arms.

3. Equipment for retaining and removing one end of a lead plate for a printing roller comprising a support having a channel therein, a pawl operating shaft having eccentrics spaced therealong rotatably mounted in said channel, an L-shaped lever pivotally mounted about its apex on each eccentric, one arm of each L-shaped lever serving as a pawl for connection to one end of a lead plate and adapted to be projected beyond and retracted within the support, the other arm of each L-shaped lever extending in a direction generally parallel to the surface of the support, a stop limiting the movement of said other arm away from said surface of the support, biasing means reacting between said support and said other arm to urge said other arm toward said stop whereby rotation of said pawl operating shaft will cause said L-shaped lever to move the pawl arm into projected or retracted position.

4. An operating structure for a movable segment mounted on a support for movement in opposite directions and to indicate in which position the segment is located comprising a lever, said segment being provided with a lever receiving aperture for removable reception of the lever, a key movably mounted in the support for engagement in a slot in the segment to fix the segment on the support, an indicating pin movably mounted on the segment and projecting outwardly therefrom and spaced from said lever receiving aperture to be observable when the lever is in the lever receiving aperture, said indicating pin being engageable with the movable key to indicate the position of the key, a pin movable transversely to the lever receiving aperture and with one end partially receivable in the lever receiving aperture and the other end movable into a registering recess in the support at the two limits of movement of the segment, said lever having a recess with closed wall portions adapted to receive the said one end of the pin whereby the movable segment may be moved to either limit of its movement and the operating lever can be removed from the lever receiving aperture only when the segment is moved to one of said limits of movement and the pin registers with corresponding registerable recess in the support.

5. The combination with a roller having a shaft rotatably mounted therein eccentric to the axis comprising means for operating the shaft for accurate adjustment on the roller including, means to support the shaft for oscillatable movement, said shaft being splined at one end thereof, a helical gear splined on the splined end of said shaft, screw threads adjacent each end of the splined portion of said shaft, a flanged bushing threaded on one of said screw threads, and a lock nut on the other of said screw threads with means to adjust the flanged bushing and lock nut to vary the axial position of the helical gear, a segmental gear mounted on said roller cooperating with said helical gear whereby arcuate movement of the segmental gear causes rotation of its associated helical gear and thereby

operation of the shaft, means to limit the movement of said segmental gear, said segmental gear being provided with a radially extending lever receiving aperture, an operating lever for reception in the radial aperture in said segmental gear, a lock key mounted in said roller and movable into a recess in said segmental gear, resilient means urging said locking key into said recess to prevent relative angular motion between said roller and said segmental gear, an indicating pin mounted in said gear segment and pressed toward said lock key to indicate the shaft position, a retaining pin mounted in said segmental gear for axial movement and of a length to extend into the radial lever receiving aperture, and into a registerable pin receiving recess in said roller and adapted to be received into a recess in the portion of the operating lever received in the lever receiving aperture in the segmental gear, said roller having a second pin receiving recess with which said pin may register at another position of said shaft and segmental gear whereby said operating lever can be inserted and removed only when said pin is in registry with one of said registering recesses.

6. The combination with a roller having a shaft rotatably mounted therein eccentric to the axis comprising means for operating the shaft for accurate adjustment on the roller including, means to support the shaft for oscillatable movement, said shaft being splined at one end thereof, a helical gear splined on the splined end of said shaft, screw threads adjacent each end of the splined portion of said shaft, a flanged bushing threaded on one of said screw threads, and a lock nut on the other of said screw threads with means to adjust the flanged bushing and lock nut to vary the axial position of the helical gear, a segmental gear mounted on said roller cooperating with said helical gear whereby arcuate movement of the segmental gear causes rotation of its associated helical gear and thereby operation of the shaft, means to limit the movement of said segmental gear, said segmental gear being provided with a radially extending lever receiving aperture, an operating lever for reception in the radial aperture in said segmental gear, a lock key mounted in said roller and movable into a recess in said segmental gear, resilient means urging said locking key into said recess to prevent relative angular motion between said roller and said segmental gear, a retaining pin mounted in said segmental gear for axial movement and of a length to extend into the radial lever receiving aperture, and into a registerable pin receiving recess in said roller and adapted to be received into a recess in the portion of the operating lever received in the lever receiving aperture.

ture in the segmental gear, said roller having a second pin receiving recess with which said pin may register at another position of said shaft and segmental gear whereby said operating lever can be inserted and removed only when said pin is in registry with one of said registering recesses.

7. A pawl construction comprising a support, a shaft mounted on said support, an eccentric mounted on said shaft with the axis of the eccentric and the axis of the shaft being closely adjacent and lying substantially within in the circumference of the shaft, a lever having two arms pivoted intermediate the ends of the arms on said eccentric, the free end of one arm providing a pawl, a first stop means on the support to limit the movement of the other arm in the pawl releasing direction, a second stop means on the support engageable with the other arm and yieldable force exerting means reacting through the other arm and the second stop means in the direction of pawl engaging movement whereby the pawl is effectively released upon movement of the eccentric in the pawl releasing movement and the pawl is yieldably forceably engaged when the eccentric is moved in pawl engaging direction to compensate for variations.

8. The invention according to claim 7 in which the second stop means includes a spring mounted on said support providing the yieldable force exerting means.

9. The invention according to claim 7 in which the second arm is a leaf spring providing the yieldable force exerting means.
